Richard Corington

UNITED STATES PATENT OFFICE.

RICHARD COVINGTON, OF WASHINGTON, DISTRICT OF COLUMBIA.

IMPROVEMENT IN SHUTTER-HINGES.

Specification forming part of Letters Patent No. 59,365, dated November 6, 1866.

To all whom it may concern:

Be it known that I, RICHARD COVINGTON, of Washington City, in the District of Columbia, have invented a new and useful Hinge for Fastening Shutters at Various Angles with the Wall; and I do hereby declare that the following is a full, clear, and exact description of the construction and operation of the same, reference being had to the annexed drawings, making a part of this specification, in which—

Figure 1 is an elevation of the hinge, and Figs. 2, 3, and 4 are plans of the same. Fig. 5 is another method of working and constructing the same invention, and is an elevation of the hinge, Figs. 6, 7, and 8 being plans of the same.

In Fig. 1, *a* and *b* are arcs of circles (or *b* may be attached to the hinge at all parts of its inner circle as well as at one end) with a common center, *c*, the arc *a* being attached at one end to the side *d* of the hinge, and the arc *b* to the side *e*. The touching surfaces of these arcs have in each semicircular vertical recesses, each of which will at various angles of the shutter find a corresponding recess, forming together a circular hole, into which a pin is dropped to fasten the hinge in that position.

There is a hole in each side of the hinge to admit the arc attached to the opposite side.

In Fig. 5, *a* is a little more than the half of a solid cylinder, the diameter of which is seen in the plans, cast solid onto one side, *b*, of the hinge, and in the closing of the hinge passing through a corresponding space cut out of the side *c* of the hinge. On the face of this cylinder *a* there are vertical semicircular recesses, each of which, on reaching the edge *d* of the side *c* of the hinge, finds a corresponding semicircular recess, forming together a hole, into which a pin, *e*, being dropped, the shutter is fastened at certain angles with the wall, or back against it.

I claim—

Constructing the hinge with a locking attachment composed of two notched segments of cylinders, lying concentric one with the other, which may be rendered immovable at any given point by the insertion of a pin in any one of the notches, substantially as described.

RICHARD COVINGTON.
